DESK STRUCTURE

Peter M. Wege, East Grand Rapids, Mich., assignor to Metal Office Furniture Company, Grand Rapids, Mich., a corporation of Michigan

Application June 13, 1935, Serial No. 26,390

2 Claims. (Cl. 45—6)

The instant invention relates to desk structures and more particularly to metal desks especially adapted for office use.

The primary objects of the present invention are to provide a desk of the character above indicated having a novel drawer section construction; to provide such a desk having a novel leg construction; to provide such a desk having a drawer pedestal comprising a skeleton portion which facilitates manufacture, permits of accuracy in alignment of component parts, enclosed by an integrally formed and jointless sheet metal sheath; and, to provide such a desk which is attractive in appearance, rugged and sturdy in construction and economical in manufacture.

An illustrative embodiment of the invention is shown in the accompanying drawings, in which:

Figure 1 is a perspective view of the metal desk;

Figure 2 is an enlarged fragmentary sectional view on line 2—2 of Figure 3;

Figure 3 is a sectional view thereof on line 3—3 of Figure 2;

Figure 4 is a fragmentary perspective sectional view of a portion of the drawer section of the desk;

Figure 5 is a fragmentary sectional view of the leg construction on line 5—5 of Figure 6;

Figure 6 is a sectional view thereof on line 6—6 of Figure 5;

Figure 7 is a sectional view of a portion of the drawer section on line 7—7 of Figure 3 but showing a drawer partly drawn outwardly to its stop;

Figure 8 is an enlarged sectional view of the drawer on line 8—8 of Figure 10 and provided with removable and adjustable plates for varying the width of the sections formed by such plates;

Figure 9 is a sectional view thereof on lines 9—9 of Figures 8 and 10;

Figure 10 is a top plan view of a drawer provided with removably adjustable plates whereby the drawer may be divided into sections of varying widths;

Figure 11 is an enlarged sectional view on line 11—11 of Figure 10 and showing the lock thereof concealed by a reinforcing element in the form of a tray;

Figure 12 is a sectional view thereof on line 12—12 of Figure 11;

Figure 13 is a sectional view on line 13—13 of Figure 11; and

Figure 14 is a fragmentary top plan view of the middle drawer.

Referring then to the drawings in which like parts of the desk structure therein shown are designated by the same numerals in the several views, the desk top 10 is supported at its opposite ends by pedestals or drawer sections, each comprising a vertically disposed stamped sheet metal rear wall 11 which is curved forwardly at its opposite marginal edges 12 to form vertically disposed spaced side walls 13 each of which is curved inwardly toward each other at their opposite forward marginal edges 14 and thence flanged rearwardly as best shown in Figure 2.

Vertically disposed angle iron members 15 are secured adjacent each of the four corners of each pedestal or drawer section as by spot welding to form vertical sleeves and drawer guide supports 16 of angle iron construction are secured to the opposite inside walls of the side walls 13 of the pedestals or drawer sections as by spot welding, all as best shown in Figure 2.

Horizontally disposed flanged channel bar drawer guides 17 are secured to the oppositely disposed forward vertical angle iron members 15 and to the drawer guide supports 16 as by spot welding, the forward ends of each drawer guide 25 being provided with a resilient drawer bumper 18 of rubber or the like which projects outwardly or forwardly therefrom and the lengths of each drawer guide are provided with a depending drawer stop 19 struck therefrom, as best shown in Figure 3.

Legs for supporting the desk at each of its four corners comprise a tubular tapered sleeve 20 having a foot 21 spring pressed thereon and having a ring 22 likewise spring pressed to the upper end thereof. An inner tubular element 23 is transversely formed of sheet metal and its adjoining marginal edges are slightly spaced apart rendering the lower tubular portion yieldingly compressible. The upper portion of the tubular element 23 is inserted and secured within vertically disposed sleeves formed by the angle iron members 15 secured to the side walls 13 and to the several side walls 13 and the end wall 11 at their junctures or at each of the four corners of the drawer pedestal as best shown in Figures 5 and 6.

Drawers for the several pedestals or drawer sections comprise spaced parallel side walls 24 whose upper marginal edges 25 are flanged inwardly thence downwardly, a front wall 26, a rear wall 27 whose upper marginal edge 28 extends above the upper marginal edges 25 of the side walls for contacting the stops 18 when the drawer is slid outwardly (see Figure 7), and a

bottom 29. The bottoms of the several drawers adjacent each of their opposite marginal lengths at 100 are first angularly formed downwardly, thence upwardly, thence outwardly, and finally upwardly to form the side walls 24, all as best shown in Figures 8 and 12. The drawer bottoms when thus slidably supported at 100 by their oppositely disposed drawer guides 17 have a portion disposed between and depending below the oppositely disposed guide supports 17 which construction provides for rigidity and nonbinding sliding operation.

The several desk drawers may if desired be provided with oppositely disposed spring tensioned arcuate plates 30 adjustably sprung between the upper marginal edges 28 and the groove formed by the depressed formation 100 in the lower marginal lengths of the opposite side walls 24 of the drawer, as best shown in Figures 8 and 9. These arcuate plates are provided with integrally formed and spaced inwardly extending transverse portions 31, 32 and spacer plates 33 may be detachably disposed therebetween. Since these arcuate plates are adjustably sprung into place, they may be moved forwardly or rearwardly along the insides of the side walls of the drawer as indicated by the double ended arrows in Figure 10 for readily changing the widths of the pockets of the sectional drawer thus formed.

In instances where the desk drawer is provided with a lock 34 rearwardly of its inside panel, the same may if desired be concealed by a tray 35 disposed rearwardly thereof which likewise reinforces the drawer as best shown in Figures 10-14. The tray best shown in Figure 11 is provided with oppositely disposed slits 36 and a transverse plate formed by folding its sides 37, 38 against themselves has its opposite ends extending through the slits, the corners 39, 40 of the

folded plate being oppositely turned outwardly at one end thereof.

It will thus be seen that the desk structure herein shown and described has a novel drawer section construction, a novel leg construction, that the desk may if desired be provided with sectional drawers which drawer sections may be readily changed as to sectional width, and that in desks which are provided with a lock, the lock may, if desired, be concealed by a reinforcing element in the form of a tray.

While but several specific embodiments of this invention have been herein shown and described, it will be understood that numerous details of the constructions shown may be altered or omitted without departing from the spirit of this invention as defined by the following claims.

I claim:

1. A drawer pedestal including a skeleton frame provided with tubular corner posts, tubular members having upper portions longitudinally split and compressibly fitted within and depending from each tubular corner post, tubular sleeves fitted on the tubular members, and means carried by the upper ends of the sleeves and supporting the skeleton frame.

2. A drawer pedestal including a skeleton frame provided with tubular corner posts, tubular members having upper portions longitudinally split and compressibly fitted within and depending from each tubular corner post, downwardly tapered tubular sleeves having their lower ends fitted on the tubular members and their upper ends spaced therefrom, and means carried by the upper ends of the sleeves and closing the space between the upper ends of the sleeves and the tubular members and supporting the corner posts and the skeleton frame.

PETER M. WEGE. 40
